UNITED STATES PATENT OFFICE.

RUDOLF ZELLENKA, OF VIENNA, AUSTRIA-HUNGARY.

METHOD OF PREVENTING THE WARPING AND UNDULATING OF XYLOLITH FLOORS.

SPECIFICATION forming part of Letters Patent No. 747,110, dated December 15, 1903.

Application filed October 3, 1902. Serial No. 125,800. (No specimens.)

To all whom it may concern:

Be it known that I, RUDOLF ZELLENKA, manufacturer, a citizen of the Empire of Austria-Hungary, residing in Vienna, Austria-Hungary, have invented a certain new and Improved Method for Preventing the Warping and Undulating of Xylolith Floors; and I do hereby declare the following to be a full, clear, and exact description of the invention, such as will enable others skilled in the art to which it appertains to make and use the same.

Floors constructed of xylolith (a compound produced by submitting a mixture of sawdust and sand or other similar mineral substances, mixed with sufficient liquid, to a very high pressure, forming a sheet resembling wood) have the well-known disadvantage that they possess a very strong tendency to warp, and for this reason their application is exceedingly limited.

This invention has for its object improved means for preventing the warping and undulating of xylolith floors, while at the same time the material is firmly secured to the supporting parts. To this end the rough floor to be covered when constructed of wood is laid with open-work or reticulated plates of sheet-iron—as, for instance, described in German Patents Nos. 45,916, 84,345, 91,182—which are firmly secured to the wooden support. Upon the floor thus furnished with the reticulated plates the xylolith is applied in the known manner, whereby the latter penetrates through the openings in the plates, so as to be in contact with the under floor itself, upon which it is then supported, and at the same time completely covers the said plates.

If, as in ships, for example, it is necessary

to cover iron floors, the plates may be screwed to the floor and the xylolith applied as before stated. In this case it is advantageous to allow the xylolith covering to harden partially and then effect a series of cross-cuts to divide the xylolith covering into separate squares of about fifty centimeters. The cross-cuts should be made with thin knife-blades and so that they are hardly visible after the hardening of the xylolith, while yet permitting the latter to yield to the alterations in the form of the iron ship construction without cracking.

In the accompanying drawings, which illustrate my invention, Figure 1 is a plan view, partly broken away; and Fig. 2 is a sectional view thereof on the line A B of Fig. 1.

In the drawings, *a* indicates the floor or foundation; *b*, the crossing rods or wires, or it may be a reticulated plate; *c*, the nails securing the rods or plates to the floor, and *d* the xylolith covering.

Having now described my invention, what I claim, and desire to secure by Letters Patent, is—

Improved method for preventing the warping and undulating of xylolith floors consisting in placing upon the supporting-surface and fastening thereto reticulated metal plate and then applying the xylolith composition until it completely covers the reticulated plate.

In testimony whereof I affix my signature.

RUDOLF ZELLENKA.

In presence of—

FRIEDRICH BINDER,
ALVESTO S. HOGUE.
